CLAIM

The ornamental design for a tire tread, as shown and
described.

DESCRIPTION

FIG. 1 is a perspective view showing the tire tread of our new
design;

FIG. 2 is a front view thereof; and,

FIG. 3 is a left side view thereof.

In the drawings, the broken lines defining the sidewall, inner
bead and the peripheral boundary between the claimed tire
tread and the unclaimed sidewall depict environmental sub-
ject matter that forms no part of the claimed design.
